(57) **CLAIM**

The ornamental design for a shoe as shown and described.

DESCRIPTION

FIG. 1 is a front perspective view of a shoe, showing an embodiment of our new design; and,
FIG. 2 is a rear perspective view thereof.

The dashed broken lines in the figures depict portions of the shoe that form no part of the claimed design. The short broken lines within the portions outlined by solid lines depict stitching, which forms no part of the claimed design. FIGS. 1 and 2 illustrate a left shoe; the right shoe is a mirror image of the left shoe, and is also claimed as an embodiment of the claimed design.
